UNITED STATES PATENT OFFICE.

ALICE H. FLANDERS, OF CHICAGO, ILLINOIS, ASSIGNOR TO A. H. FLANDERS COMPANY, OF CHICAGO, ILLINOIS, A CORPORATION OF ILLINOIS.

DESIGN FOR A WOMAN'S BLOUSE.

55,993.

Specification for Design.

Patented Aug. 10, 1920.

Application filed June 18, 1920. Serial No. 390,029. Term of patent $3\frac{1}{2}$ years.

To all whom it may concern:

Be it known that I, ALICE H. FLANDERS, a citizen of the United States, residing at Chicago, in the county of Cook and State of Illinois, have invented a certain new, original, and ornamental Design for a Woman's Blouse, (No. 363,) of which the following is a specification, reference being had to the accompanying drawing, forming part thereof.

Fig. 2 is a similar view of the back side of the same.

I claim:

The ornamental design for a woman's blouse, as shown.

ALICE H. FLANDERS.
